UNITED STATES PATENT OFFICE

2,543,649

LINKAGE FOR HYDRAULIC ACTUATORS

Lawrence B. Wales and Merton O. Hodges, Marblehead, Mass., assignors to General Electric Company, a corporation of New York

Application July 12, 1950, Serial No. 173,444

7 Claims. (Cl. 74—53)

1

This invention relates to mechanical linkage mechanism for communicating motion from a hydraulic motor to a member positioned thereby, particularly to mechanical linkages for positioning the inlet valves of a prime mover such as a steam turbine.

In steam turbines having capacities on the order of 15,000 kw., it is conventional practice to subdivide the first-stage nozzles into arcuate segments, with separate chambers in the steam inlet chest arranged to feed each segment, separate valves being provided to control the admission of steam to the respective valve chest chambers. Ordinarily these valves are arranged in a row with a common actuating mechanism for opening the valves in desired sequence. A form of this mechanism which has become quite common includes a valve lift lever disposed substantially horizontally above the steam chest with one end pivoted to a fixed fulcrum supported by a bracket from the turbine casing, the other end carrying a roller cam follower engaged by a contoured cam positioned by suitable hydraulic or other motor means. The fixed fulcrum may be a common shaft passing through bushings in the ends of the respective valve lift levers. Likewise the cams for positioning the other ends of the levers may be mounted on a common shaft rotatably positioned by the actuating motor, and suitably contoured and oriented with respect to each other so that the valves are opened in proper sequence and positioned as required by the turbine operating schedule. A connecting link or rod is pivoted to the mid-portion of the valve lift lever and to the valve stem.

In mechanism of this type, enormous forces must be applied to the turbine valves. For instance, in a 15,000 kw. turbine, it may be necessary to apply a force as much as 10,000 lbs. in opening a given valve against full steam inlet pressure. At the same time, the governing of a steam turbine must be done quite precisely and with maximum reliability. It is therefore necessary that the linkage connecting the valve positioning motor with the valve stems be simple, extremely rugged, and, in particular, arranged to have an absolute minimum of friction in the pivot joints.

Accordingly, the object of this invention is to provide a suitable linkage for turbine valve lift mechanism of the multiple cam type with a special frictionless pivot arrangement between the connecting rod and the valve lift lever arranged so that only rolling contact occurs between the connecting rod bearing surface and

2

the pivot. It will of course be appreciated that the invention may also be applicable to other machines where similar problems are encountered.

Other objects and advantages will be apparent from the following description taken in connection with the accompanying drawings in which Fig. 1 shows, partly in section, a turbine valve actuating linkage arranged in accordance with the invention; Fig. 2 is a top view of the linkage of Fig. 1; Fig. 3 is a detail view of a modified form of the valve lift lever with its special rolling contact connecting pivot; and Fig. 4 is a transverse section taken on the plane 4—4 in Fig. 3.

In general, the special pivot arrangement which is a principal characteristic of this linkage comprises a cylindrical pivot rod fixed to the valve lift lever and cooperating with flat transverse parallel spaced bearing surfaces formed in the connecting rod end portion, the space between these bearing surfaces being somewhat greater than the diameter of the pivot rod so the pivot engages only one of the bearing surfaces at a given time and has pure rolling contact therewith, so that friction is reduced to the absolute minimum.

Referring now more particularly to Fig. 1, valve stem 1 is positioned by a pivoted connecting rod 2 the upper end of which is connected by the specially arranged rolling contact pivot shown generally at 3 to the mid-portion of valve lift lever 4, which has its left-hand end carried on a fixed fulcrum 5, while the right-hand end thereof is provided with a roller cam follower 6 adapted to be engaged by an actuating cam 7. The upper portion of the turbine valve inlet casting 8 supports a heavy, horizontally disposed frame plate member 9 secured by studs 10 to the inlet casing. Disposed through opening 11 in casting 8 is a lower valve stem bushing 12 secured in a bore through plate 9 by means of a circumferential flange 13 engaged by a retaining ring 14 (which may be divided into two or more segments for convenience in assembly) secured by screws 15 to the frame plate 9. Cast integral with the frame member 9 is a central upwardly extending cylindrical portion 16 having a flanged end portion 17 carrying an upper valve stem bushing 18 secured in the frame end flange 17 by means of a flange 19 engaged by a retaining ring 20 held by suitable threaded fastenings 21.

As will be apparent from Fig. 1, the valve stem 1 is constrained for linear reciprocating motion 55 by the upper and lower bushings 18, 12, and car-

ries on its upper projecting end portion an abutment member 22 suitably secured to the valve stem, as by being threaded thereon, and having a circumferential shoulder portion defining a spring seat 23. For biasing the stem 1 in the valve-closing direction, a heavy coil spring 24 is disposed with its lower end portion engaging the seat 23, while its upper end portion engages a similar seat ring 25, the latter being supported in fixed relation to the frame 9 by means of two or more radially extending projections 26a through which are disposed elongated tubular nut members 26 having a depending portion 27, the lower end 28 of which is threadedly received on a stud 29 secured at its lower end in the flange portion 17 of the frame plate 9. The circumferential flange 23 of abutment 22 may be provided with radially extending portions having semi-circular cutouts indicated in dotted lines at 23a as cooperating with the studs 29 so that rotation of the abutment 22 is prevented by engagement of these cutout portions with the studs. While not essential to the present invention, it may be noted that the biasing force of spring 24 may be readily adjusted by turning the nuts 26 so that they move longitudinally on the threaded end of stud 29.

As will be understood from Fig. 1, the valve stem abutment 22 is provided with a pair of opposed upwardly extending ears 30 in which are fixed the respective ends of the lower connecting rod pivot 31. It will of course be obvious to those skilled in the art that the cooperating bore through the lower connecting rod end may be provided with a Babbitt metal lining or a suitable bronze Lushing to provide a low friction bearing surface engaging the mid-portion of the pivot 31. The special rolling contact pivot for the upper end portion of the connecting rod will be described in more detail hereafter.

The valve lift lever 4 is preferably fabricated from steel plates by welding and consists of parallel spaced side plates 32 having welded therebetween at the left-hand end a fulcrum bushing 33 with a bronze bushing 34 or equivalent bearing means engaging the common fixed fulcrum shaft 35. This shaft has one extreme end portion fixed in a support block 36 secured by threaded fastenings 37 to the upper end of a bracket 38, the bottom end portion of which is suitably secured by welding or bolting to the frame plate member 9.

The bearing bushing 34 of the valve lift lever is retained on the fixed fulcrum shaft 35 between the support block 36 and a retaining collar 39 (Fig. 2) which may conveniently be secured to shaft 35 by a set screw 40. It will be understood of course that the shaft 35 is extended to provide the support for the other valve lift levers (not shown) and has a suitable number of spaced support blocks corresponding to that shown at 36. Where they receive the ends of the pivot rod 41, the side plates 32 are thickened by having welded thereto reinforcing plates 42. The pivot rod 41 may be secured in position by means of a set screw 43 or equivalent means.

At the right-hand end of the valve lift lever 4, a pair of bushings 44 are welded to the side plates, one of which bushings has fixed therein an end portion of the cam roller follower shaft 45, as by a set screw 44a. As may be seen in Fig. 2, the cam follower roller 6 is disposed between the support bushings 44 and is carried on the shaft 45 by suitable bearing means, which may be either a Babbitt or bronze bushing type of bearing or

an anti-friction bearing such as the well-known "needle-type" roller bearing.

The actuating cam 7 which engages the cam roller follower 6 is carried on a shaft 47 journalled in suitable pillow blocks 48 secured to a portion 38a of the bracket 38. The motor means for rotatably positioning the cam 7 is not illustrated because it is not material to an understanding of the present invention.

The structure of the valve lift lever 4 is completed by a pair of top plate members 49, 50, which may be welded along the edges thereof to the side plates 32 and at the respective ends to the bushings 33, 44. At the left-hand side of the rolling contact pivot 3, a bottom plate 51 is similarly welded to the edges of side plates 32. Between the pivot 3 and the right-hand end of lever 4 there is provided a downwardly extending "knock-down arm" 52, the function of which will be described hereinafter. This arm may be formed integral with or welded to the side plates 32. The depending lower end portion of this knock-down lever defines a cam surface 53 adapted to be engaged by a cylindrical "knock-down pin" 54, which is fixed in the side of and projects axially from the cam 7.

Referring now to the rolling contact pivot at 3, it will be noted that the upper end portion 2a of connecting rod 2 is provided not with the usual cylindrical bore but a transversely elongated slot 55. The top and bottom walls of this slot form flat parallel surfaces indicated at 55a, 55b, which are the bearing surfaces for the rolling contact engagement with the pivot 41. Normally the upper bearing surface 55a is biased into engagement with the top surface of pivot 41 by the action of the main spring 24. In this condition there is a small but significant clearance space between the lower bearing surface 55b and the lower side of pivot 41, this clearance being indicated at 56.

The method of operation described hereinafter requires that the connecting rod end portion 2a always be biased to the right relative to pivot 41; and to this end an auxiliary coil spring 57 is provided, having one end hooked into a hole in the top plate 49 as will be obvious from Fig. 2. The other end of coil spring 57 loops around a pin 58 threadedly received in the top of connecting rod end portion 2a. It will be apparent from Fig. 1 that the effect of auxiliary spring 57 is to bias the connecting rod end portion 2a to the right so that ordinarily pivot pin 41 will occupy the extreme left-hand side of slot 55 when the valve gear is in the "valve-closed" position, as represented by Fig. 2. As indicated above, the pivot 41 will ordinarily engage the top bearing surface 55a by reason of the bias imposed by main spring 24.

It will be seen in Fig. 2 that the reinforcing portions 42 of the lever side plates form comparatively close clearances with the adjacent side faces of the connecting rod end portion 2a, so that any rotational movement of the connecting rod 2 about its longitudinal axis relative to pivot rod 41 is prevented.

To illustrate the method of operation, assume that the actuating cam 7 begins to rotate in the clockwise direction, with the result that roller follower 6 begins to rise. This of course means that the valve lift lever 4 begins to rotate counter-clockwise about the fixed fulcrum 5. This motion causes pivot pin 41 to bear against the upper surface 55a and raise the connecting rod 2, thus "cracking" the turbine valve open. Now if cam 7 continues to rotate clockwise its

contoured outer surface will cause the roller follower 6 to rise progressively and the lever 4 to continue rotating in the counter-clockwise direction around pivot 5. This rotational movement of lever 4 also causes the pivot rod 41 to rotate relative to the connecting rod bearing surface 55a. This relative rotation between pivot 41 and surface 55a causes the cylindrical pivot to roll on the surface 55a, with the result that the connecting rod end portion 2a moves to the left, against the bias of coil spring 57. Because of the enormous forces transmitted between the pivot 41 and the bearing surface 55a, the frictional resistance to slipping between these surfaces prevents any slipping so that there is true rolling contact. Even in the inoperative condition, with no steam pressure on the valves, the biasing force of the main coil spring 24 will create enough static friction between pivot 41 and bearing surface 55a that there will be no relative slipping therebetween.

It will be understood that the bearing surface 55a is sufficiently long in a transverse direction, relative to the angular travel of the valve lift lever 4, that throughout the normal movement of the valve stem vertically the pivot 41 simply rolls freely along the surface 55a, without any slippage therebetween and without reaching the right-hand end of the slot 55. By the time the cam 7 reaches its limiting position, with the valve stem 1 raised to the "wide-open" position, the pivot 41 will have rolled along surface 55a until it almost, but not quite, reaches the right-hand end of the slot 55.

If the cam 7 now rotates in the counter-clockwise direction, the cam roller 6 is permitted to move downwardly, the valve lift lever 4 pivots clockwise about the fixed fulcrum 5, and the heavy biasing spring 24 causes the valve spindle 1 to move downwardly in the valve closing direction. This motion causes the pivot 41 to rotate in a clockwise direction, whereupon the rolling contact between pivot 41 and surface 55a effects movement of the connecting rod end portion 2a to the right. When the cam returns to the valve closed position, the pivot 41 will again have reached the left-hand side of slot 55, the position shown in Fig. 1.

The above-described operation in the opening and closing directions is that which normally occurs. However, this arrangement also incorporates provision for the comparatively rare case where the turbine valve stem sticks in the open position, so that the bias of the spring 24 is not sufficient to move it towards closed position. If this sticking persists as the cam 7 rotates counter-clockwise in the closing direction, the cam follower roller 6 will leave the surface of cam 7. When this happens, the weight of the valve lift lever 4 tends to move it clockwise about fulcrum 5, the connecting rod 2 remaining in its elevated position due to the sticking of the valve stem 1. This means that pivot 41 moves out of frictional engagement with surface 55a; and the instant this occurs, the auxiliary biasing spring 57 will snap the connecting rod end 2a to the right until pivot 41 occupies the left-hand portion of slot 55, as shown in Fig. 1. If rotation of cam 7 in the counter-clockwise direction now continues, with valve stem 1 stuck in open position, the knock-down pin 54 will engage the surface 53 of arm 52, thus applying a force to the lever 4 tending to rotate it clockwise about pivot 5, so as to positively force the stem 1 in the valve-closing direction.

It will be seen that, when the lever 4 is forced downwardly by engagement of the knock-down pin 54 with the arm 52, the clearance space 56 between the lower surface of pivot pin 41 and the bearing surface 55b closes so that the bearing engagement between pivot 41 and the lower bearing surface 55b forces the connecting rod 2 downwardly. Now as the lever 4 continues to rotate clockwise, the clockwise rotation of the pivot 41 relative to lower bearing surface 55b causes it to roll thereacross, with the result that the connecting rod end portion 2a again moves to the left and the pivot 41 approaches the right-hand end of slot 55.

If this forced closing movement of the valve overcomes the tendency to stick, then the spring 24 may become effective to quickly bias the connecting rod 2 downwardly so that the cam roller follower 6 again engages the cam 7. During this movement, however, the pivot 41 will move out of engagement with the lower bearing surface 55b; and instantly the spring 57 will again pull the connecting rod end portion 2a to the right so that pivot 41 is returned to the left-hand side of the slot 55. Thus the next time cam 7 moves clockwise in the valve opening direction, the pivot 41 will be at the left-hand side of slot 55 and ready to roll to the right-hand side thereof as described above for the normal operation of the mechanism.

It will now be apparent that regardless of whether the cam 7 forces the lever 4 upwardly, so that pivot 41 rolls to the right across bearing surface 55a, or whether the knock-down pin 54 forces the lever 4 downwardly, with the pivot 41 rolling to the right across bearing surface 55b, there is always true rolling contact between pivot 41 and connecting rod end portion 2a. Thus a most important source of frictional resistance in the actuating linkage is eliminated. The auxiliary biasing spring 57 serves to insure that any time contact is broken between the pivot 41 and one of the bearing surfaces 55a, 55b, the upper connecting rod end portion 2a will be quickly moved to the right so that the pivot 41 will be in position to travel across the bearing surfaces 55a, 55b as may be required by the operating conditions.

While, theoretically at least, it would appear possible to apply this rolling contact type of pivot to the lower end of connecting rod 2 also, in practice this does not achieve sufficient improvement to warrant the additional mechanical complication because if the connecting rod 2 is of a reasonable length, the angular movement of the lower pivot 31 relative to the connecting rod is only a very few degrees so that friction at this point is of no great consequence. On the other hand, the upper connecting rod bearing has been found to be an important source of troublesome friction in turbine valve gear of this type; and the rolling contact arrangement described herein is found to effect a substantial improvement in rendering the operation of the valve actuating mechanism friction-free and reliable.

It will of course be apparent to those skilled in the art that the mechanical details of the connecting rod 2 and of the main and auxiliary biasing springs associated with it are susceptible to an enormous number of modifications, as are also the details of the valve lift lever and the means for positioning it.

The details of the rolling contact arrangement may also be considerably varied. For instance, Figs. 3 and 4 show an alternate arrangement in

which the enlarged upper end of the connecting rod 2 is replaced by a pair of spaced abutments in the form of a lower cylindrical block 60 having a central bore threaded onto the valve spindle 2 and seating against a lock nut 61. The cylindrical upper abutment 62 is likewise threaded onto the connecting rod 2 and provided with a lock nut 63.

In this modification, the pivot pin 64 is provided with a conical bore 65 therethrough, through which the connecting rod 2 projects freely. The respective ends of pivot pin 64 are carried in bushings 66, 67 (Fig. 4), which may conveniently be welded to the outside of the lever arm side plates 68, 69, the latter corresponding to the side plates 32 in Fig. 1. The pivot pin may be locked in one of these bushings by means of a set-screw, as shown at 70 in Fig. 4. The mechanical details of the fixed fulcrum pivot 5, valve lift lever 4, cam follower roller 6, and the "knock-down" lever 52 may be generally as described above in connection with Figs. 1, 2.

It will be apparent that the lower face 62a of abutment 62 forms a flat bearing surface corresponding in function to the upper bearing surface 55a in Fig. 1, while the upper surface 60a of the lower abutment 60 forms a bearing surface corresponding to that identified 55b in Fig. 1. As will be apparent in Fig. 4, the bias of spring 24 ordinarily maintains the upper bearing surface 62a in contact with the upper surface of pivot rod 64. Also, the lower surface of pivot rod 64 forms the clearance space shown at 56. It will be apparent that the magnitude of this clearance space may be readily adjusted by suitably positioning the abutments 60, 62 on the threaded portions of connecting rod 2.

The auxiliary biasing means for the upper end of connecting rod 2 consists here of a spring-biased plunger 71 (Fig. 3) slidably disposed in a cylindrical recess in a cross-brace 72 which may be welded at either end to the side plates 68, 69. As will be apparent from Fig. 3, the coil spring 73 surrounds a reduced diameter portion of the plunger 71 and is disposed in the recess in cross-brace 72. The left-hand end of plunger 71 slides in the recess and engages the side of abutment 60 so as to bias it to the left. The other reduced-end portion of plunger 71 projects through a hole in brace 72 and carries a stop member which may be in the form of a nut 74 threadedly received on the plunger end portion. In order to accurately limit the extent to which the upper connecting rod end portion may be moved to the left by the biasing plunger 71, an adjustable stop is provided in the form of a cross-brace 75 welded to the side plates 68, 69 and carrying a threaded stop member 76 provided with a lock nut 77.

Although the general function is the same, the detailed operation of this modification is different in some respects from that of Figs. 1, 2. The tapered hole 65 through the pivot pin 64 is of course so proportioned that for all positions of the lever 4 there will be no mechanical interference between connecting rod 2 and the sides of recess 65. In Fig. 3, the mechanism is shown in the valve closed position, with main spring 24 biasing the bearing surface 62a into contact with the top of pivot pin 64. When the lever 4 moves counter-clockwise about fixed fulcrum 5 in the valve opening direction, the pivot 64 rotates counter-clockwise also, with the result that rolling contact between surface 62a and pivot rod 64 causes the connecting rod 2 to approach the left-hand side of the recess 65.

Conversely, when the knock-down lever 52 is engaged to force the lever 4 clockwise in order to free a sticky valve, the pivot 64 moves downwardly to engage the bearing surface 60a whereupon the biasing plunger 71 moves the upper end of the connecting rod 2 to the left against stop 76. Thus when pivot 64 contacts the lower bearing surface 60a the clearance space between connecting rod 2 and the recess 65 will be so disposed that the pivot 64 can roll across the lower bearing surface without mechanical interference between pivot and connecting rod.

Thus in each of the above-described modifications the rolling contact pivot is so arranged that for either mode of operation the cylindrical surface of the pivot rod rolls across one of a pair of opposed flat bearing surfaces and out of contact with the other, while auxiliary biasing means automatically move the end of the connecting rod relative to the pivot rod so that the clearance space provided therebetween will always permit such free-rolling contact. Thus the friction at the most troublesome point in the mechanism is reduced to a minimum, even below that which would be obtainable with conventional ball or roller anti-friction bearings. At the same time this pivot joint requires no lubrication whatever since there is no relative rubbing under load.

It will be apparent to those skilled in the art that many other alterations and substitutions of equivalents might be made, and it is desired to cover by the appended claims all such changes as fall within the true spirit and scope of the invention.

What we claim as new and desire to secure by Letters Patent of the United States is:

1. In a mechanical linkage including a lever pivoted to a fixed fulcrum at one end thereof and having a connecting link pivoted to a spaced portion thereof, the combination of rolling contact bearing means for the connecting link pivot comprising a cylindrical pivot member fixed to the lever with the axis thereof parallel to the axis of rotation of the lever about the fixed fulcrum, the connecting link end portion having walls defining substantially flat spaced parallel bearing surfaces disposed at opposite sides of the pivot member and substantially normal to the length of the connecting link, the spacing between said surfaces being greater than the diameter of the pivot whereby a clearance space is defined at all times between at least one of said flat bearing surfaces and the pivot, and means biasing the connecting link end portion relative to the pivot, whereby when the pivot is disengaged from both bearing surfaces said biasing means moves the connecting link end portion transversely to provide a clearance space between pivot and connecting link so disposed that, upon subsequent engagement of the pivot with one of the flat bearing surfaces, free-rolling contact may take place between pivot and bearing surface as the lever rotates about the fixed fulcrum.

2. In a mechanical linkage including a lever pivoted to a fixed fulcrum at one end thereof and having a connecting link pivoted to a spaced portion thereof, the combination of rolling contact bearing means for the connecting link pivot comprising a member fixed to the lever and having a portion forming a cylindrical bearing surface the axis of which is parallel to the axis of rotation of the lever about the fixed fulcrum, a member secured to the connecting link end portion and defining a flat bearing surface normal

to the length of the link and disposed adjacent said pivot member, and spring means biasing the connecting link end portion transversely relative to the pivot whereby, when the pivot bearing surface is disengaged from the flat bearing surface, the biasing means moves the link end portion transversely to provide a clearance space between pivot and link so disposed that, upon subsequent engagement of the pivot bearing surface with the flat bearing surface, free-rolling contact may take place between pivot and bearing surface as the lever rotates about the fixed fulcrum.

3. In a mechanical linkage including a lever pivoted to a fixed fulcrum at one end thereof and having a connecting link pivoted to a spaced portion thereof with means for constraining the other end of the link for rectilinear movement in a direction substantially normal to the length of the lever, the combination of rolling contact bearing means for the connecting link pivot comprising a member fixed to the lever and having a cylindrical pivot bearing surface the axis of which is disposed parallel to the axis of rotation of the lever about the fixed fulcrum, the connecting link end portion defining an opening through which the cylindrical pivot member is disposed, the opposed walls of said opening defining substantially flat spaced parallel bearing surfaces disposed substantially normal to the length of the link and spaced apart a distance greater than the diameter of the cylindrical pivot bearing surface whereby a clearance space is defined at all times between at least one of said flat bearing surfaces and the pivot bearing surface, and means biasing the connecting link end portion relative to the pivot bearing surface, whereby when the pivot is disengaged from both bearing surfaces said biasing means moves the connecting link end portion transversely to provide a clearance space between pivot and link so disposed that, upon subsequent engagement of the pivot with one of said bearing surfaces, free-rolling contact may take place between pivot and bearing surface as the lever rotates about the fixed fulcrum.

4. In a mechanical linkage including a lever pivoted to a fixed fulcrum at one end thereof and having a connecting link pivoted to a spaced portion thereof with means for constraining the other end of the link for rectilinear movement in a direction generally normal to the length of the lever, main spring means biasing the link to one extreme of its range of movement and means for positioning the lever against the bias of said main spring, the combination of rolling contact bearing means for the connecting link pivot comprising a member fixed to the lever and having a cylindrical pivot bearing surface the axis of which is disposed parallel to the axis of rotation of the lever about the fixed fulcrum, the end portion of the connecting link defining an opening through which the cylindrical pivot member is disposed, opposite side walls of said opening forming flat parallel bearing surfaces disposed substantially normal to the length of the link, the spacing between said parallel bearing surfaces being slightly greater than the diameter of the cylindrical pivot member whereby a clearance space is defined at all times between at least one of said flat bearing surfaces and the pivot bearing surface, the length of said opening transverse to the length of the link being substantially greater than the diameter of the cylindrical pivot bearing surface, and auxiliary means biasing the connecting link end

portion relative to said cylindrical pivot in a direction away from the fixed fulcrum, whereby, when the cylindrical pivot is disengaged from both the flat bearing surfaces, said auxiliary biasing means moves the connecting link end portion transversely away from the fixed fulcrum so that upon subsequent engagement of the pivot with one of the flat bearing surfaces free-rolling contact may take place between pivot and bearing surface as the lever rotates about the fixed fulcrum.

5. In a mechanical linkage including a lever pivoted to a fixed fulcrum at one end thereof and having a connecting link pivoted to a spaced portion thereof with means constraining the other end of the link to move in a substantially rectilinear direction generally normal to the length of the lever, main spring means biasing the link in a direction away from the lever, and means for positioning the lever against the bias of the main spring, the combination of rolling contact bearing means for the connecting link pivot comprising a member fixed to the lever and having a circumferential portion forming a cylindrical pivot bearing surface, said pivot member defining a transverse recess through which the connecting link end portion is disposed with substantial clearances between link and pivot, a pair of spaced members adjustably secured to the connecting link end portion and forming a pair of flat parallel bearing surfaces disposed adjacent diametrically opposite portions of the cylindrical pivot bearing surface, the spacing between said parallel bearing surfaces being greater than the diameter of the cylindrical pivot surface whereby a clearance space is defined at all times between at least one of the flat surfaces and the pivot, and auxiliary spring means biasing the connecting link end portion relative to the lever in the direction towards the fixed fulcrum, whereby, when the pivot surface is disengaged from both flat bearing surfaces, the auxiliary spring means biases the connecting link end portion transversely so as to be disposed adjacent the side of the recess in the pivot nearer the fixed fulcrum in order that upon subsequent engagement of the pivot bearing surface with one of said flat bearing surfaces, free-rolling contact may take place between pivot and bearing surface as the lever rotates about the fixed fulcrum.

6. In a mechanical linkage including a lever pivoted at one end to a fixed fulcrum and having a connecting link pivoted to a spaced portion thereof, the combination of rolling contact bearing means for the connecting link pivot comprising a member fixed to the lever and having a circumferential portion defining a cylindrical pivot bearing surface with its axis disposed parallel to the axis of rotation of the lever about the fixed fulcrum, said pivot member defining a transverse recess through which the connecting link end portion is disposed with substantial clearances between link and pivot, the link end portion defining at least one flat bearing surface disposed substantially normal to the length of the link and disposed adjacent said pivot member, and spring means biasing the connecting link end portion transversely relative to the pivot, whereby, when the pivot surface is disengaged from the flat bearing surface, said biasing means moves the link end portion transversely to provide a clearance space between pivot and link so disposed that, upon subsequent engagement of the pivot bearing surface with the flat bearing surface, free-rolling contact

11

may take place between pivot and bearing surface as the lever rotates about the fixed fulcrum.

7. In a mechanical linkage including a lever pivotally fixed to a fulcrum at one end thereof and having a connecting link pivoted to a spaced portion thereof with means constraining the other end of a link to move in a substantially rectilinear direction generally normal to the length of the lever, spring means biasing the link in a direction away from the lever, and means for positioning the lever in either direction, the combination of rolling contact bearing means for the connecting link pivot comprising a member fixed to the lever and having a cylindrical pivot bearing surface, said pivot member defining a transverse recess through which an end portion of the connecting link is disposed with substantial clearances between link and pivot, a pair of spaced members secured to the connecting link end portion and forming a pair of flat parallel bearing surfaces disposed normal to the length of the link and adjacent diametrically opposite portions of the

12

cylindrical pivot bearing surface, the spacing between said parallel bearing surfaces being greater than the diameter of the cylindrical pivot whereby a clearance space is defined at all times between at least one of the flat surfaces and the pivot, and auxiliary spring means biasing the connecting link end portion relative to the lever transversely towards the fixed fulcrum, whereby, when the pivot surface is disengaged from both flat bearing surfaces, the auxiliary spring means biases the connecting link end portion transversely to the side of the recess in the pivot nearer the fixed fulcrum in order that, upon reengagement of the pivot bearing surface with one of the flat bearing surfaces, free-rolling contact may take place between pivot and bearing surface as the lever rotates about the fixed fulcrum.
